METHOD OF AND SHEET FOR MAKING FLAT
OPENING BOOKS

Charles E. Gale, Quincy, Mass.

Application September 14, 1932
Serial No. 633,088

8 Claims. (Cl. 281—40)

This invention relates to a novel method of preparing and assembling leaves for use in the manufacture of a flat-opening book and to a novel sheet produced by one step of the method. 5 The invention will best be understood by reference to the following description when taken in connection with the accompanying drawings illustrating the novel method and sheet, while its scope will be pointed out more particularly in 10 the appended claims.

In the drawings:

Fig. 1 is a plan of one face of a sheet resulting from the first step in the method;

Fig. 2 is a plan of the other face of the sheet;

Fig. 3 is a perspective view of one of the scoring blocks used in the preparation of the sheet; and

Fig. 4 is a perspective view illustrating the step of assembling the leaves for binding.

Referring to the drawings and to the method 20 and sheet illustrated therein, there is shown in Figs. 1 and 2 a sheet of paper 10 comprising a plurality of leaf areas, herein thirty-two, for example, designated for convenience by the numerals 11 to 42 inclusive. As shown, the leaf areas 25 are defined by sets of horizontal and vertical, broken lines, but these lines do not in fact appear upon the sheet and are shown in the drawings merely to indicate the lines along which the sheet is to be cut as one step in the method.

If, as in the present example, the leaves are 30 to be printed, the printing on the entire face of the sheet is accomplished in one impression by a printing form comprising a plurality of plates locked in a chase in the usual manner, thus to produce printed areas 43 to 74 inclusive, whose 35 outlines are indicated by rectangles shown in dotted lines. The reverse face of the sheet is shown in Fig. 2 with printed areas 75 to 106 inclusive, all of which are printed in one impression by a printing form comprising a plurality 40 of plates locked in a chase in the usual manner.

To produce a flat-opening book, the leaf areas 45 are provided with scored lines 107 to 138 inclusive, each differing in location transversely of its length from the scored lines of other areas. This is conveniently accomplished simultaneously 50 with the printing of the printed areas 43 to 74 inclusive by the use of a set of scoring blocks, one of which is shown in Fig. 3 and designated 139, 55 the same being provided with a sharp V-shaped scoring rule 140, the location of which corresponds with the desired scored line of a given leaf area. The printer, in making up the form, places in the chase, beside each printing plate, a 60 scoring block parallel with that edge of the plate

corresponding to the edge of the printed area, which is to be adjacent to the binding edge of the leaf, thus to weaken the paper and to impart to it the requisite degree of flexibility to enable it to bend freely and to allow the book to be 65 opened flat. It is, of course, understood that each scored line shall be differently and properly located with respect to other lines, so that after the sheet has been printed and scored, it will be cut by any suitable means into leaves (see 70 Fig. 4) and the leaves assembled for binding, so that the distances of the scored lines from the binding edges 141 shall increase in inverse ratio to the proximity to the middle plane X—X of the leaf assembly. The ends of the scored lines appear as a V in the assembly.

For convenience in assembling the leaves after the cutting of the sheet, the difference in location of the scored lines is progressive in a given series and is also progressive from one series to 75 another series. As shown in Fig. 1, for example, the leaf areas 11 to 26, inclusive, are in four series designated A, B, C and D, respectively. In the series A, the difference in the location of the scored lines is progressive from the leaf area 80 11 to and including the leaf area 14, and the progression continues from series A through series D, the distances of the scored lines from the adjacent edges of the printed areas diminishing, or to put it differently, the distances of the scored 85 lines from the prospective binding edges increases progressively. The several series A, B, C and D are to constitute the front part of the book, that is to say, from the first leaf to the middle, the 90 number of leaves depending upon the total number of leaves the book is to have. In the case of a book having a considerable number of leaves, it may require a whole sheet or even several sheets to produce the required number of leaves 95 from the front to the center of the book.

In the example shown, however, the book is to have thirty-two leaves (sixty-four pages), and the leaf areas for the front part of the book are comprised in the four series A, B, C and D. The leaf areas for the back part of the book are comprised in series E, F, G and H, and in this series the progression runs in the opposite direction, so to speak, as to the relative locations of the scored lines. The differences in series A, B, C and D may be likened, for example, to an ascending 100 progression and the differences in series E, F, G and H to a descending progression. In each progression there is a leaf area having a scored line corresponding in location with the location of the scored line of a leaf area of the other pro- 105

gression. For example, the leaf areas 11 and 42 are alike in respect to the location of their respective scored lines 107 and 138.

Thus it is evident that, with these progressions, 5 after the sheet is cut into leaves, the assembling of the leaves in the manner shown in Fig. 4 becomes an easy matter because the stacking of the leaves can take place in regular order from leaf to leaf of one series and from one series to another throughout the entire number required for the leaf assembly.

The invention contemplates the possibility of folding the sheet to produce a signature or section instead of cutting the same into separate 15 leaves, but while this may be done with the sheet by proper location of the scored lines to correspond with the manner of folding, nevertheless, the cutting of the sheet into leaves is preferred because of the greater resulting accuracy in the 20 location of the scored lines in the finished product.

Having thus described the method and one embodiment of the sheet which is produced by one step of the method, but without limiting myself thereto, what I claim and desire by Letters Patent to secure is:

1. As a new article of manufacture, a sheet for use in the manufacture of a book, the same comprising a plurality of leaf areas, each provided 30 with a scored line, the location of which transversely of its length differs from that of the scored lines of other areas.

2. As a new article of manufacture, a sheet for use in the manufacture of a book, the same comprising a series of leaf areas, each provided with 35 a scored line, the location of which transversely of its length differs from that of the scored lines of other areas of the series, the difference being progressive in said series.

40 3. As a new article of manufacture, a sheet for use in the manufacture of a book, the same comprising a plurality of series of leaf areas, each area being provided with a scored line, the location 45 of which transversely of its length differs from that of the scored lines of the other areas of a plurality of the series, the difference being progressive in each series and the progression continuing from one series through another series.

50 4. As a new article of manufacture, a sheet for use in the manufacture of a book, the same comprising a plurality of leaf areas, each provided with a scored line, the location of which trans-

versely of its length differs from that of the scored lines of the other areas, the difference being progressive according to a predetermined plan, a part of the progression being a decrease of the distance from the line to adjacent side 80 of the leaf area, and a part being an increase of the distance from the line to the adjacent side of the leaf area.

5. As a new article of manufacture, a sheet for use in the manufacture of a book, the same comprising a plurality of leaf areas, each provided with a scored line, the location of which transversely of its length differs from that of the scored lines of other areas, there being two series 90 of leaf areas, each series being like the other in respect to the location of its scored lines, but one series being reversely arranged with respect to the other.

6. As a new article of manufacture, a sheet for use in the manufacture of a book, the same comprising a plurality of leaf areas, each provided with a scored line, the location of which transversely of its length differs from that of the scored lines of other areas, the differences being in two sequences, one comparable with an ascending progression and the other with a descending progression.

7. The art of preparing book-leaves for binding, comprising preparing a sheet by providing the same with a plurality of scored lines located, 105 respectively, within leaf areas which are to become leaves, the lines differing from one another in location transversely of their lengths in respect to the respective leaf areas, and subsequently assembling the leaves face to face for 110 binding, so that the distances of the scored lines from the binding edges shall increase in inverse ratio to the proximity of the leaves to the middle plane of the leaf assembly.

8. The art of preparing book-leaves for binding, comprising simultaneously printing the leaf areas and scoring each leaf area along a line parallel with one edge of the printed area, the lines differing from one another in location transversely of their lengths in respect to the respective leaf areas, cutting the sheet into leaves, each having a printed area and a scored line, and collating the leaves for binding, so that the distances of the scored lines from the binding edges 120 shall increase in inverse ratio to the proximity of 125 the leaves to the middle plane of the assembly.
